D. Lynde

Inventor:
John Ed. Phillips

United States Patent Office.

JOHN E. PHILLIPS, OF PHILADELPHIA, PENNSYLVANIA.

Letters Patent No. 63,090, dated March 19, 1867

IMPROVED PRESS STRAINER.

The Schedule referred to in these Letters Patent and making part of the same.

TO ALL WHOM IT MAY CONCERN:

Be it known that I, JOHN E. PHILLIPS, of Philadelphia, in the State of Pennsylvania, have invented a new and useful Press Strainer; and I do hereby declare that the following is a full and exact description thereof, reference being had to the accompanying drawings, and to the letters of reference marked thereon.

Figure 1 represents my strainer with its base-plate, detachable funnel and hopper, and cylinder with the plunger therein.

Figure 2 represents a detachable screw-plunger, with its screw-ring, by which it may be substituted for the plunger and hopper seen in fig. 1.

In Figure 3 seven different disks, strainers, and grates are represented, designed for the various purposes for which my invention is intended.

Figure 4 represents the cylinder, with its adjustable cylindrical cover and two screw-rings herein more fully described.

The object of my invention is to furnish, for various domestic uses, a new article of manufacture capable of use for the preparation of different kinds of food, and for making wine, cider, and similar beverages. Also designed for the use of druggists and confectioners in the preparation of tinctures, extracts, perfumery, and other things of the same nature.

In the drawings, *a* denotes an annular base-plate, with a flange, by which it may be screwed fast to a table. The lower half of the cylinder *d* is perforated, and the band or cylindrical cover *e* is adjustable, so as to slide down over the perforated portion of cylinder *d*. The base ring *f* is provided with an internal screw, by which ring *f* is secured to the lower end of cylinder *d*, the latter being provided with a corresponding ring with screw-thread thereon, as seen in fig. 4 of the drawings. The hopper *c* fits into the top of cylinder *d*, and is detachable, and the hand-plunger *b* may be used with the hopper; but when the screw-plunger is employed, the hopper *c* is dispensed with, and a larger one may be placed on the annular screw-holder *j*, and the latter being provided with an internal screw-thread, which fits over the upper screw-ring of cylinder *d*, may be firmly fastened thereto. The lower ring *f* is furnished with an annular flange to receive the flange of the funnel *g*, also to support the disks, screens, or grates, and strainers, represented in fig. 3. The outer projecting flange of screw-ring *f* is of a form corresponding with the face of base-plate *a*, on which it rests to support the whole structure. Instead of supporting the cylinder by means of the base-ring *f*, this ring, and its corresponding screw-ring upon the bottom of the cylinder, may be dispensed with, when the cylinder will pass down through the fixed annular base-plate *a*, and rest thereon by the shoulder formed by the bottom of the upper screw-ring upon the cylinder *d*. When thus modified, the lower end of the cylinder *d* will be provided with an internal flange or ring to receive and support the strainers, disks, &c.

In using my improved strainer for working butter, the band or cover *e* may be raised to expose the perforated portion of cylinder *d*; the disk *l* is placed in the bottom of the cylinder, and rests upon the flange or ring therein; when the butter is taken from the churn and placed in the cylinder; the hand-plunger *b* is then pressed down thereon, causing the butter to be strained in jets through the perforations of the cylinder. During this operation, the cylinder may be set into a bucket of water, by which means the buttermilk will be readily separated. Instead of removing the cover *e* from the perforated portion of cylinder *d*, the perforated disk *m* may be used, and the pressure may be applied by either the hand-plunger *b* or the screw-plunger represented in fig. 2. The same operation will serve for straining lard; and by substituting finer sieves, screens, or strainers, placed between the stronger grates, the same operation will serve for separating the juices from berries, apples, and similar fruits for wine, &c. The same operation will, with one or more of the coarser grates, be found convenient in the preparation of numerous articles of food, as apple butter, pie sauces, pumpkins, and other vegetables. Besides the uses mentioned, and others of a like nature, it will be obvious that my improved device may be used for stuffing sausages. For straining milk the fine gauze wire screen will be used; and for stoning cherries the grate, composed of a series of rings marked *n*, will be used. The milk strainer, which may be used daily, is constructed of a fine wire gauze, with an annular ring cast thereon. The metals which should be employed in the structure should be such, incorrosive metals, as may be easily cleansed, and at the same time will impart no unpleasant flavor to the culinary articles prepared by my strainer. Hair cloth,

or fibrous textile fabrics, may be interposed between the grates as strainers or for filtering purposes. My hand-plunger, *b*, is constructed with one plane and one convex face, to correspond with the forms of the screens and grates, and the circumference may be provided with a metal band to prevent the wood from swelling by dampness; and an India-rubber ring packing may be used to prevent liquids from being forced upwards by the pressure in the cylinder.

Having fully described my invention and the manner of using the same, what I claim, and desire to secure by Letters Patent, is—

The perforated cylinder *d* and band cover *e*, in combination with the disks, strainers, and a screw-plunger, and base-plate, *a*, operated substantially as described for the purposes specified.

In testimony hereof I have hereto set my hand this 26th day of July, 1866.

JOHN EDW. PHILLIPS.
